Letters Patent No 1835 dated Oct 20th 1835

Design for the Plates of a Parlor Stove.

The schedule referred to in these Letters Patent and making part of the same.

To all whom it may concern:

Be it known that Isaac De Fouche, of the City and County of Saint Louis, and State of Missouri, have invented or produced a new and original Design for the Plates of a Parlor Stove; and I do hereby declare that the following is a full and exact description of the same, reference being had to the accompanying drawings and to the letters of reference marked thereon, making a part of this specification, in which,

Fig. 1. represents a perspective view of the stove, and Fig. 2. the back plate.

A. A. fig. 1 represents the front plate, ornamented with hollows x. x. each terminating above and below with a triple ogee head ornament, as shown. B. B. represents what I call wings, consisting of scroll work interlaced with an oak branch having acorns and leaves, each terminating with a dolphin C. at bottom. D. D. are doors, ornamented with beads and hollows radiating from a centre, as shown. E. represents an urn, ornamented with open work in the cover F. and base G. and with hollows in the body H. I. represents the urn stand, ornamented with open work, as shown. The whole surmounted by the scroll ornament J. The back plate fig. 2. is ornamented with hollows x. x. each terminating above and below with a triple-ogee bead ornament in a similar manner to the front plate A.A. It is deeply indented at K and perforated at I.I. M. represents the foot, of which there are four, all exactly similar, ornamented with a shield N and terminating at the bottom with the beads O.

Having thus described my Design for Plates of Parlor Stove, what I claim as new therein and desire to secure by Letters Patent, is,

The ornamental configuration and Design for Plates of Parlor Stove, as herein described and shown in the annexed drawings.
